APPARATUS FOR DRILLING WELLS

Clement B. Patton, Columbus, Ohio

Application June 9, 1937, Serial No. 147,343

10 Claims.

(Cl. 255—4)

My invention relates to apparatus for drilling wells. It has to do, more particularly, with apparatus for drilling wells into the earth for oil, gas, water, sulfur or other minerals found below the earth's surface. It relates more specifically to the rotary type of well-drilling apparatus.

With the rotary method of well-drilling now commonly in use it is necessary to have a driving shaft, composed of a plurality of sections coupled together, running from the drilling tool at the bottom of the hole upwardly through the hole to the surface where the driving power unit is located. Obviously, because it is necessary for the driving shaft to be so long, it is quite costly. Due to the extreme length of the driving shaft, considerable power will be required for rotating the shaft and the bit connected to the end thereof. Furthermore, because of the extreme length of the driving shaft, it requires considerable time and effort to progressively connect the sections thereof together and lower it into the well casing. Also, when the tool is pulled from the casing it is necessary to provide powerful means for lifting the heavy drive shaft from the casing and considerable time and effort is required for uncoupling the sections of the drive shaft. Also, with this method of drilling much power is needed to operate the expensive equipment necessary to force water down through the drill stem and back to the surface on the outside of the drill stem to carry away drillings.

Several devices have been proposed in the past in an attempt to overcome these disadvantages. Some of these devices have embodied an electric motor located in the casing directly adjacent the drilling tool. However, these prior art devices have been of such a structure that they have not been successful or practical. Another difficulty experienced in the prior art is the provision of a satisfactory tool which will undercut the casing to allow lowering thereof but will fold up so that it can be raised without removing the casing. It is desirable to provide a satisfactory grinding type drilling tool, which is needed in hard structures, but such a tool is not provided with most prior art devices. The well-drilling apparatus which I have provided overcomes all of the above-indicated disadvantages and is successful and practical.

One of the objects of my invention is to provide a well-drilling apparatus of the rotary type which embodies a power unit for rotating the drill and which is adapted to be located in the well casing directly adjacent the drilling tool so that it will

not be necessary to have a driving shaft extending from the tool to the surface.

Another object of my invention is to provide the above-indicated device in combination with a well-drilling tool which is of such a nature that it will undercut the casing to allow lowering thereof but which will fold up so that it may be moved through the casing.

Another object of my invention is to provide well-drilling apparatus of the type indicated which may be quickly and easily lowered into the casing or raised through the casing.

Another object of my invention is to provide well-drilling apparatus of the type indicated which is of simple structure but which is of very sturdy construction and which will effectively and economically drill the well.

Another object of my invention is to provide a well-drilling device of such a type that the casing is carried within a few feet of the bottom of the bore so that the side walls of the bore will be protected from movement of the drilling device thereby diminishing tendency of the side walls to cave in.

In its preferred form my invention contemplates the provision of a well-drilling unit which is adapted to be disposed within the well casing at the lower end thereof. This unit embodies an electric motor and a well-drilling tool located directly adjacent each other. The well-drilling tool is rotated by means of an angular drilling stem which slides through the motor and is connected to the drilling tool. The drilling tool is of such a nature that at the time it is lowered or raised through the well casing it will be folded up and will not interfere with movement of the well-drilling unit through the casing. However, when it reaches the lower end of the casing, the tool will automatically unfold and will project beneath the casing so that it will undercut the casing and permit lowering thereof. Folding and unfolding of the well-drilling tool is accomplished automatically merely by raising and lowering the well-drilling unit.

The preferred embodiment of my invention is illustrated in the accompanying drawings wherein similar characters of reference designate corresponding parts and wherein:

Figure 1 is a perspective view showing my well-drilling unit in operative position.

Figure 2 is a vertical section taken through my well-drilling unit.

Figure 3 is a horizontal section taken substantially along line 3—3 of Figure 2.

Figure 4 is a horizontal section taken substantially along line 4-4 of Figure 2.

Figure 5 is a perspective view, partly broken away, of the well-drilling tool or bit and the 5 means for controlling folding and unfolding thereof, the bit being shown unfolded or in operative position.

Figure 6 is a similar view but showing the bit folded up or in inoperative position.

10 Figure 7 is a perspective view illustrating a different type of bit.

With reference to the drawings, I have illustrated my well-drilling apparatus as comprising mainly a power unit 1 and to tool unit 2 which 15 is driven by the unit 1.

The unit 1 is illustrated best in Figure 2. It comprises an upper casing 3 of tubular form, a lower casing 4 of tubular form and an intermediate tubular portion 5 which is threaded to the 20 lower end of member 3 and the upper end of member 4 and joins such members together. Thus, the members 3, 4 and 5 form a substantially cylindrical housing. This housing has its upper edge tapered inwardly as at 6 and has an opening 7 formed in the top thereof. The bottom of the housing is substantially closed by means of the enlarged upper end 8 of a substantially tubular member 9. This member 9 has a portion 10 threaded onto the lower end of the 25 portion 4 of the housing. The lower edge of the enlarged portion 8 of member 9 has teeth 11 formed thereon which are adapted to fit into corresponding notches formed on the interior of a collar 12 which is disposed in cooperative relationship thereto when the well-drilling device is 30 in operative position within the well casing 13. This collar 12 is threaded on the lower end of the well casing as at 14. The interfitting portions of member 8 and the member 12 serve to prevent 35 bodily rotation of my well-drilling apparatus.

I provide an electric motor indicated generally by the numeral 15 which is disposed mainly within the member 4 of the housing but part of which extends up into the member 5. This electric motor may be of the usual type. The motor 45 comprises field magnets 16, carried by the member 4, an armature 17, disposed within the magnet 16 and carried by a motor shaft 18, and motor brushes 19, carried by the member 5 of the housing. The lower end of member 17 is flared 50 as at 20 and has a wearing surface plate 21 attached thereto which can be removed and replaced. The plate 21 rests on a plate 22 which is provided with a depending annular shoulder 23 that fits into a corresponding annular groove 55 formed in the top of member 9. Oil-intake valves 24 are provided for carrying oil into the chamber 25 surrounding portion 20 of member 17 for oiling the contacting surfaces of plates 21 and 60 22. A collar 26 at the top of chamber 25 prevents oil from being thrown upwardly into the motor. The motor shaft 18 extends downwardly 65 through the top of member 9. A packing gland 27 is provided between the interior of the member 9 and the exterior of the lower end of the shaft 18.

The upper end of the motor shaft 18 extends into a sleeve or journal 28. The journal or sleeve 28 has its upper end threaded to the upper end 70 of shaft 18 as a 29. The sleeve 28 is adapted to rotate within a bearing housing 30. This bearing housing 30 has an enlarged portion 31 which is threaded into the upper end of the member 5 of the housing. A bearing 32 is slipped into 75 the bearing housing 30 and is prevented from

rotating by means of the cooperating flattened portion indicated at 33 in Figure 4. A packing nut 34 is threaded onto the upper end of the bearing housing 30. An oil duct 35 is provided for oiling the bearing 33. Sleeve 28 is provided with a cup 38 on its lower end for catching oil that drips from the bearing 32. A wire 36 passes downwardly past member 34 and is connected to a contact member 37 of the motor. 5

It will be apparent that both the upper and lower end of the motor are sealed and, consequently, there will be no danger of water reaching the interior of the motor. When the motor is operated the shaft 18 will rotate due to rotation of the armature 17. The sleeve 28 will rotate within the bearing 32. The bearing 32, the housing 30 and the packing gland nut 34 will all be stationary. 10

The motor should be wired so as to produce a low number of revolutions per minute and it 15 should be self-starting. It can either be made of a single segment or a number of segments. The motor speed should also be variable as the type of drilling tool being used and the kind of strata 20 in which the tool is drilling will have different 25 effects on the motor speed.

The motor shaft 18 is hollow and has an opening of square cross-section, as indicated in Figure 4, extending therethrough. A drilling stem or shaft 39 of square cross-section extends through 30 the opening in the shaft 18 and projects from each end thereof. Since the shaft 39 is of square cross-section and the opening in the hollow shaft 18 is of similar cross-section, rotation of the motor shaft 18 will cause rotation of the shaft 39. 35 However, the shaft 39 may be of any other desired angular cross-section.

The upper end of the shaft 39 is rounded so 40 that it can rotate in a guide member 40. It passes through an opening in this member and is connected thereto by means of a nut 41 threaded on the upper end of the shaft. The guide member 40, as illustrated in Figure 3, has notches 42 in its outer end which cooperate with vertically extending guide ribs 42 formed on the interior of 45 the member 3 of the housing. Thus, the guide member 40 serves to center the upper end of the shaft 39 but permits vertical movement thereof. Abutments 43 are provided at the upper and lower ends of the ribs 42 to limit vertical movement 50 of the guide member 40. The ribs 42 and the shaft 39 are longer than shown in the drawings in order to permit sufficient downward movement of the tool as it drills through the material. The guide member 40 has a yoke 44 connected 55 thereto to which the lower end of cable 45 is connected. By means of this cable the entire apparatus may be raised or lowered in the casing and vertical movement of shaft 39 can be controlled. The cable 45 also may carry the power 60 cable leading to the electric motor. A switch 46 is provided for starting the motor and a switch 47 is provided for stopping the motor. These switches are carried by the member 3 and are adapted to be operated automatically when the 65 guide member 40 contacts therewith. The member 3 carries adjacent its upper end a plurality of radially extending lugs 48. These lugs 48 are pivoted to member 3 and are normally forced outwardly by means of springs. They serve to 70 center the upper end of the housing within the well casing. However, when the well-drilling apparatus is pulled upwardly through the casing, the guide member 40 will contact with the inner ends of the lugs 48 and cause them to fall 75

downwardly and inwardly into the slot 49 in member 3 in which they are disposed.

The shaft 39 extends downwardly through the member 9 and has an enlarged square portion 50 on its lower end. This portion 50 is disposed mainly within a housing 51 which encloses the mechanism that controls folding and unfolding of the tool or bit. The upper end of the enlarged portion 50 passes through a square opening in the upper end of the housing 51 as at 52. The upper end of the housing 51 is bevelled as at 53 and the extreme lower edge of member 9 is correspondingly bevelled at 54. A plurality of resilient lugs 55 are secured to the upper bevelled end 53 of housing 51. When the shaft 39 is in its uppermost position the surfaces 53 and 54 will be in contact with each other and the lugs 55 will extend upwardly into the interior of member 9. The enlarged portion 50 of shaft 39 will at this time force projections 56 on the ends of the lugs into sockets 57 formed on the interior of member 9. When the lugs are in this position they serve to connect the housing 51 to the member 9. It is desirable for the housing 51 to be connected to member 9 during raising and lowering of the apparatus through the well casing.

Within the housing 51 a compression spring 58 is disposed in surrounding relation to the enlarged portion 50 of shaft 39. This compression spring bears against the upper end of the housing 51 and its lower end bears against a further enlarged bearing portion 59 formed on the shaft 39. This bearing portion 59 is square and slides vertically within the interior of the housing 51 which is of similar cross-section. The member 59 has a transversely extending slot 60 formed therein. This slot has a vertical portion and an outwardly curved portion 61 at its lower end. The side walls of the housing 51 which are adjacent to the ends of the slot 60 are provided with slots 62. Each of these slots 62 comprises a vertical portion having a curved portion 63 at its lower end which is curved in a direction opposite to that of the curved portion 61 of slot 60. It will be noted from Figure 6 that the slot 62 is slightly out of alignment with the slot 60. In reality the upper end of the slot 62 is disposed substantially in alignment with the extreme lower end of the curved portion 61 in slot 60. A pin 64 is passed through the slots 60 and 62 when the portion 59 of the shaft 39 is in its uppermost position within the housing 51. At this time the lower end of the curved portion of the slot 60 will be in alignment with the upper ends of slots 62, as indicated in Figure 6. The pin 64 pivotally carries a pair of downwardly extending curved connecting members 65. The upper portions of these members 65 are disposed within the housing 51 between the member 59 and the wall of the housing, cut-away portions 66 being provided in the outer surface of member 59 to permit swinging movement of member 65 about the pivot pin 64. It will be noted that the slots 62 are formed in opposite side walls of the housing 51 substantially midway between the edges of the side walls. The slots 62 are offset relative to the slot 60. However, the curved portions 63 of the slots 62 extend over the slot 60 while the curved portion 61 of the slot 60 extends over the slots 62. Furthermore, it will be noted that the lower end of the housing 51 has its other side walls cut away as at 67 so that the lower end of the housing is of substantially inverted U-shape, the downwardly extend-

ing portions or arms 68 thereof having their lower ends rounded as at 69. The extreme lower end of the members 65 are pivotally connected to a block or bit-carrying member 70 at a point adjacent one edge of this member. This member 70 is disposed within the arms 68 and is pivoted thereto as at 71 adjacent the edge of the block or member 70 opposite to the edge where the members 65 are connected. The member 70 has a square boss 72 on its upper surface adapted to cooperate with a square socket 73 (Figure 2) formed in the lower end of the member 59.

The member 70 carries oppositely projecting grinders 74 which are rotatably mounted thereon by means of spindles 75. These grinders 74 extend outwardly from the member 70 through the spaces 67 between the portions 68 of the housing 51.

In the operation of my apparatus, assume that the casing 13 is in position in the earth and the well-drilling apparatus is adapted to be lowered into the casing. The drilling tool will be folded up so that the grinders 74 thereof will be within the tool housing as indicated in Figure 6. The device will be hanging by the cable 45 which will pull the shaft 39 to its uppermost position. This causes the member 59, as indicated in Figure 6, to be in its uppermost position and the spring 58 to be compressed. At this time the pin 64 will lie in the extreme lower end of the curved portion 61 of slot 60. It will project through the slots 62 at the upper ends thereof. The member 70 and the tool bit carried thereby will have been at this time swung upwardly into vertical position by the members 65. The tool housing 51 will be connected to the member 9 by means of the lugs 55, the projections 56 of which will be forced into the socket 57 by means of enlarged portions 50 of shaft 39 which will be disposed upwardly within the member 9. The lugs 48 will be forced inwardly and the tool will be folded up. Consequently, the entire well-drilling apparatus may then be lowered into the casing.

The apparatus is lowered into the casing, the lower end of which is spaced a predetermined distance from the bottom of the hole, by means of the cable 45 until it reaches the lower end of the casing where the collar 8 on the housing interferes with the collar 12 on the lower end of the casing. This will prevent bodily rotation of the apparatus within the casing. At this time downward movement of the housing is stopped. Continued feeding of the cable 45 downwardly into the casing will cause the shaft 39 to move downwardly through the hollow motor shaft 18. The guide member 40 will move downwardly therewith. The lugs 48 will, consequently, be permitted to swing outwardly and center the upper end of the housing within the well casing. As the shaft 39 moves downwardly through the motor, the enlarged portion 50 will slide downwardly through the upper end of the tool housing 51. This movement will be aided by spring 58. The member 59 will move downwardly and as it moves downwardly the pin 64 which is disposed in the curved portion 61 of slot 60 will move downwardly through the slot 62. This downward movement of member 59 will cause the members 65 to swing member 70 about the pivot 71 towards a horizontal position. When the pin 64 reaches the curved lower ends 63 of the slots 62, the bits 74 of the tool will be horizontally disposed. The curved portions 63 of

slots 62 serve to lock the tool in horizontal position until the pin 64 is actually pulled upwardly by means of shaft 39. It will be obvious that upward forces tending to cause the member 70 to swing about the pivots 71 will ordinarily merely force the pin 64, by means of member 65, into the extremity of the curved portion 63 of slots 62. The curved portion 61 of slot 60 similarly functions to lock the tool in vertical position until the shaft 39 is actually moved downwardly.

As indicated, the tool is now in horizontal position. However, the member 59 is still spaced from the member 70 and the housing 51 is still connected to member 9 by lugs 55. It is important for the grinding members of the tool to reach horizontal position before member 51 moves down away from member 9 in order that there will be no danger of the tool striking the bottom of the hole before it is swung outwardly completely. Continued downward movement of shaft 39 will cause the member 59 to move closer to the member 70. This further movement of member 59 will cause the pin 64 to occupy a position in the upper end of the slot 60. When the member 59 contacts with the member 70, the boss 72 will fit into the socket 73. The member 51 will also move away from the member 9, as indicated in Figure 1. Substantially at the instant when the member 59 reaches the member 70, guide member 40 contacts with switch 46 and permits current to pass to the motor. This will rotate the shaft 39 and the drill tool connected to the lower end thereof.

As the tool drills the hole, the shaft 39 will move downwardly to progressively feed the tool through the material. When the shaft reaches the limit of its downward movement, the member 40 will contact switch 47 and interrupt flow of current to the motor. Operation of the motor will stop and a meter, which may be provided at the surface, will indicate the drilling has stopped. The well-drilling device may then be withdrawn, and the drillings may be bailed out. The casing may then be lowered farther into the bore and the drilling operation be again performed, as before. It will be understood that the lower part of the bore or hole will contain water. The water will surround the electric motor and keep it cool. However, no water will reach the interior of the motor because it is tightly sealed. The tool housing, being square, will serve to agitate the water in the lower part of the hole and will prevent the borings from forming a sediment at the bottom of the hole.

It will be apparent from the description of the operation of lowering the apparatus into the well casing that when the apparatus is raised from the casing by means of the cable 45, the tool will automatically fold up in the manner illustrated in Figure 6.

The tool illustrated in Figures 5 and 6 is adapted to be used when drilling rock or other hard substance. It will be noted that the cone-shaped grinding members 74 are removably mounted on the inclined spindles 75. The inclination of the spindles 75 is such that the bottom surface of the grinder 74 will be substantially horizontally disposed, as indicated in Figure 2. A rotatable cutting member or grinder 74' is disposed on the bottom of member 70 in order to remove material at the center of the hole below the tool unit.

When drilling through soft substance, it is desirable to have a tool of the type illustrated in Figure 7. This tool embodies a pair of oppositely

projecting rigidly supported arms 74a. These arms are flat on the bottom but the top surface thereof is inclined to form a knife edge on one edge thereof. The knife edges of the two arms are oppositely disposed. A removable cutting member 74b may be applied to the lower surface of each arm and is provided with a portion which projects over the cutting edge thereof. A transversely extending cutting edge 74b is provided on the lower surface of member 74a for cutting away material at the center of the hole.

It will be apparent from the above description that I have provided well-drilling apparatus which is of the rotary type and which embodies a power unit that occupies a position directly adjacent the drilling tool. Consequently, maximum power and maximum efficiency is obtained with the power unit. It is not necessary to have a long driving shaft extending from the surface to the bottom of the casing. Furthermore, the power unit and the drilling tool are connected to each other by sturdy connections. The connections between the power unit and the drilling tool control folding and unfolding of the tool. The tool is automatically moved into inoperative position to permit movement through the well casing whenever the device is lifted through the casing. Furthermore, merely lowering apparatus into the bottom of the casing causes the tool to swing into operative position.

Many other advantages will be apparent from the preceding description, the drawings and the following claims.

Having thus described my invention, what I claim is:

1. A well-drilling apparatus of the rotary type adapted to be positioned at the end of a well casing comprising a power unit, a tool unit, said tool unit embodying a tool member mounted for movement between an operative position where it drills and underreams the hole below the well casing and an inoperative position for permitting movement thereof through the well casing to and from working position, a drilling stem adapted to be rotated by the power unit and being connected to the tool member for rotating it, said drilling stem being slidable longitudinally through the power unit, said drilling stem being connected to the tool member in such a manner that longitudinal movement thereof will cause movement of said tool member between operative and inoperative positions.

2. A well-drilling apparatus of the rotary type adapted to be positioned at the end of a well casing comprising a power unit, a tool unit, said power unit embodying an electric motor, said tool unit embodying a tool member mounted for movement between an operative position where it drills and underreams the hole below the well casing and an inoperative position where it will not interfere with movement thereof through the well casing to and from working position, a drilling stem adapted to be rotated by the electric motor, said drilling stem being slidable longitudinally through the electric motor, said drilling stem being connected to the tool member in such a manner that longitudinal movement thereof will cause movement of said tool member between operative and inoperative positions.

3. A well-drilling apparatus of the rotary type adapted to be positioned at the end of a well casing comprising a power unit, a tool unit, said power unit embodying an electric motor, said tool unit embodying a tool member mounted for

- movement between an operative position where it drills and underreams the hole below the well casing and an inoperative position where it will not interfere with movement thereof through the well 5 casing to and from working position, said electric motor having a hollow drive shaft with an opening extending therethrough of angular cross-section, a drilling stem of a corresponding angular cross-section extending through said shaft and 10 being slidable longitudinally through said hollow shaft, said drilling stem being connected to the tool member in such a manner that longitudinal movement of the stem will cause movement of said tool member between operative and inoperative 15 positions.
4. A well-drilling apparatus of the rotary type adapted to be positioned at the end of a well casing comprising a power unit, a tool unit, said power unit embodying an electric motor, said 20 tool unit embodying a tool member mounted for swinging movement between an operative position where it projects outwardly and underreams the hole below the well casing and inoperative position where it is so disposed that it will not interfere with movement thereof through the well 25 casing to and from working position, said electric motor having a hollow drive shaft with an opening extending therethrough of angular cross-section, a drilling stem of a corresponding angular 30 cross-section extending through said shaft and being slidable longitudinally through said hollow shaft, said drilling stem being connected to the tool member in such a manner that longitudinal movement of the stem will cause swinging movement 35 of the tool member between operative and inoperative positions, and means operating automatically in response to longitudinal movement of said stem for controlling operation of said motor.
5. In combination with a well casing, a well- 40 drilling apparatus of the rotary type adapted to be positioned at the end of the well casing and comprising a power unit and a tool unit, said power unit comprising a housing having an electric motor disposed therewithin, said tool unit embodying a tool member mounted for movement 45 between an operative position where it drills and underreams the hole below the well casing and an inoperative position where it will not interfere with movement thereof through the well 50 casing to and from working position, means on the lower end of the casing for engaging said housing to prevent rotation thereof relative to said casing, a drilling stem adapted to be rotated by the electric motor, said drilling stem being 55 slidable longitudinally through the electric motor, said drilling stem being connected to the tool member in such a manner that longitudinal movement thereof will cause movement of said tool member between operative and inoperative 60 positions.
6. In combination with a well casing, a well-drilling apparatus of the rotary type adapted to be positioned at the end of the well casing and comprising a power unit and a tool unit, said power unit comprising a housing having an electric motor disposed therewithin, said tool unit embodying a tool member mounted for movement 65 between an operative position where it drills and underreams the hole below the well casing and an inoperative position where it will not interfere with movement thereof through the well casing to and from working position, means on the lower end of the casing for engaging said housing to prevent rotation thereof relative to said casing, a drilling stem adapted to be rotated by the elec- 70
- tric motor, said drilling stem being slidable longitudinally through the electric motor, said drilling stem being connected to the tool member in such a manner that longitudinal movement thereof will cause movement of said tool member between operative and inoperative positions, and means extending from the surface through the casing and connected to said apparatus for raising and lowering it through the casing, said means controlling longitudinal movement of said drilling 75 stem.
7. In combination with a well casing, a well-drilling apparatus of the rotary type adapted to be positioned at the end of the well casing and comprising a power unit and a tool unit, said power unit comprising a housing having an electric motor disposed therewithin, said tool unit embodying a tool member mounted for movement between an operative position where it drills and underreams the hole below the well casing and an inoperative position where it will not interfere with movement thereof through the well casing to and from working position, means on the lower end of the casing for engaging said housing to prevent rotation thereof relative to said casing, a drilling stem adapted to be rotated by the electric motor, said drilling stem being slidable longitudinally through the electric motor, said drilling stem being connected to the tool member in such a manner that longitudinal movement thereof will cause movement of said tool member between operative and inoperative positions, means extending from the surface through the casing and connected to said apparatus for raising and lowering it through the casing, said means controlling longitudinal movement of said drilling stem to prevent rotation thereof relative to said casing, a drilling stem adapted to be rotated by the electric motor, said drilling stem being slidable longitudinally through the electric motor, said drilling stem being connected to the tool member in such a manner that longitudinal movement thereof will cause movement of said tool member between operative and inoperative positions, means extending from the surface through the casing and connected to said apparatus for raising and lowering it through the casing, said means controlling longitudinal movement of said drilling stem and means operating automatically in response to longitudinal movement of said drilling stem for controlling said electric motor.
8. In combination, a drilling stem, a drilling tool housing connected to the end of said stem, said stem being movable longitudinally relative to said housing, a drilling tool pivoted to said housing for movement between operative position where it projects from the housing and inoperative position where it is disposed substantially within the housing, means for connecting the end of the drilling stem to the tool in such a manner that longitudinal movement of the stem will cause movement of the tool between operative and inoperative positions, said means comprising members pivotally connected to the drilling stem by a pivot pin passing through a transversely extending vertically disposed slot formed in said stem, said members having their opposite ends connected to the tool member at a point spaced from the point where the tool member is pivotally connected to the housing, the ends of said pivot pin also extending through vertically disposed slots formed in adjacent side walls of said housing, said last-named slots being offset relative to said slot in said stem, the lower ends of the slots formed in the casing and the lower end of the slot formed in the stem having oppositely curved portions each of which extends over the adjacent slot.
9. A well-drilling apparatus of the rotary type adapted to be positioned at the end of a well casing comprising a power unit, a tool unit, said tool unit embodying a tool member mounted for swinging movement between an operative position where it projects outwardly and drills and underreams the hole below the well casing and an inoperative position where it is so disposed that it will not interfere with movement thereof

through the well casing to and from working position, a drilling stem adapted to be rotated by the power unit and being connected to the tool member for rotating it, said drilling stem being 5 slideable longitudinally through the power unit, said drilling stem being connected to the tool member in such a manner that longitudinal movement thereof will cause swinging movement 10 of said tool member between operative and inoperative positions.

10. In combination, a drilling stem, a drilling tool housing, said stem having its end passing into said housing and being slideable longitudinally relative to said housing, a block pivoted to the 15 lower end of said housing and having a drilling

tool member mounted thereon, movement of said block about its pivot being adapted to move the tool member between an inoperative position where it is disposed substantially within the housing and an operative position where it projects 5 from the housing, means for connecting the end of the drilling stem to the block in such a manner that longitudinal movement of the stem will cause the block to move about its pivot, said stem having an angular socket formed in its lower end 10 adapted to receive an angular portion formed on said block when the tool member is in operative position so that the tool member may be rotated by the stem.

CLEMENT B. PATTON. 15
